DIGITAL CLOCK WITH ANALOG SECONDS INDICATOR

Emil John Niznik, Lake Geneva, Wis., assignor to
Bunker Ramo Corporation

Filed May 2, 1974, Ser. No. 466,133

Term of patent 14 years

Int. Cl. D10—01

U.S. Cl. D10—15

FIG.1

FIG.2

FIG.4

FIG.3

FIG. 1 is a front elevational view of a digital clock with analog seconds indicator showing my new design;

FIG. 2 is a left side elevational view thereof, the right side being substantially a mirror image thereto;

FIG. 3 is a top plan view thereof, the bottom being substantially a mirror image thereto; and

FIG. 4 is a rear elevational view thereof.

I claim:

The ornamental design for a digital clock with analog seconds indicator, as shown and described.
